UNITED STATES PATENT OFFICE.

JAMES M. BRADY, OF DUBOIS, PENNSYLVANIA.

LICENSE HOLDER.

Application filed June 15, 1922. Serial No. 568,604.

To all whom it may concern:

Be it known that I, JAMES M. BRADY, a citizen of the United States, residing at Dubois, in the county of Clearfield and State 5 of Pennsylvania, have invented certain new and useful Improvements in License Holders, of which the following is a specification.

This invention relates to holding devices for cards or tags and is designed more 10 especially as a holding means for a hunter's license card. It is customary to carry such cards upon the outside of the hunting coat or jacket where they will be plainly exposed to view, and heretofore various crude 15 devices have been employed for holding the cards in place. Such devices have been unsatisfactory for various reasons; they have not generally been adapted to protect the card from the elements nor have they usually 20 been constructed to effectually protect the card from mutilation. The present invention has as one of its primary objects to provide a holding device or pocket for such a card either attached to the hunting coat 25 or jacket at the time of manufacture or sold as a separate article to be attached by the purchaser and which device will so house the card as to effectually protect the same from the elements and from contact with 30 obstructions such as tree branches and the like which would be liable to mutilate the card.

Another object of the invention is to provide a device for the purpose stated so constructed that it may be readily attached to the garment and likewise readily detached therefrom so as to permit of the introduction or removal of the license card, the invention further contemplating the construction 40 of the device in such a manner as to prevent loss or displacement of the card after it has been placed in the pocket.

In the accompanying drawing:

Figure 1 is a view in elevation of one form 45 of the device attached to a hunting jacket;

Fig. 2 is a detail horizontal sectional view on the line 2—2 of Fig. 1;

Fig. 3 is a vertical sectional view on the line 3—3 of Fig. 1;

Fig. 4 is a view similar to Fig. 2 illustrating a modified form of the invention.

That form of invention shown in Figs. 1, 2 and 3 of the drawings is adapted to be attached or applied to the coat or jacket at the 55 time of manufacture, whereas that form illustrated in Fig. 4 is designed more par-

ticularly to be placed upon the market as an independent article and attached by the purchaser. Except for the attaching means, the two forms are substantially identical and in 60 each instance the device comprises a pocket which is indicated in general by the numeral 1 and which may be formed from any suitable material such for example as leather. This pocket comprises a back 2 and a front 65 3 and the two members of the pocket are united along their upper and lower margins by lines of stitching indicated by the numeral 4. The ends or lateral portions of the two members, however, are left mutually disconnected so that the license card, which is indicated by the numeral 5, may be inserted 70 into the pocket through either end thereof. The front 3 of the pocket is provided with a sight opening 6 through which the face of 75 the card may be displayed, and a transparent pane 7 of izing glass, celluloid, or the like, is secured within this opening so as to protect the card and yet leave the same visible.

The supporting and attaching means for the pocket 1, in that form of the invention shown in Figs. 1, 2 and 3, comprises a strap 8 which is stitched or otherwise secured, as at 9, at a point preferably midway between 80 its ends to any suitable portion of the garment as, for example, the back, where such license cards or tags are ordinarily worn, and the portions of the strap at the opposite sides of its attached intermediate portion are 85 first passed through slots 10 formed in the back 2 of the pocket and into said pocket and thence through other slots 11 formed in the said back of the pocket and to the exterior thereof. The said portions of the strap are 90 then passed through slots 12 and 13 formed in the lateral portions of the back 2 and front 3, respectively, of said pocket, and the ends of the strap are provided with snap fastening elements 14 engageable with companion elements 15 secured to the garment. The strap 8 extends across the garment as 95 will be evident by reference to Fig. 1 and therefore extends across the pocket 1, and inasmuch as the end portions of the strap 100 are passed through the slots 12 and 13 which register when the lateral portions of the front and back of the pocket are brought into contact, the license card or tag disposed within the pocket will be retained in 105 place as effectually as though some distinct and separate means were provided for the

purpose. The provision of the snap fasteners comprising the elements 14 and 15 of course permits of ready attachment and detachment of the pocket and supporting strap, 5 and it will be understood that the license card or tag may be removed and inserted through either end of the pocket by merely withdrawing that end portion of the strap 8 which is passed through the slots 12 and 10 13 at said end of the pocket. Of course, the reinsertion of the strap end through the slots will serve to again close the end of the pocket and prevent loss or displacement of the card or tag.

15 In that form of the invention shown in Fig. 4 of the drawing, the strap corresponding to the strap 8 is indicated in general by the numeral 16 and comprises an intermediate section 17 and end sections 18, which latter sections are stitched or otherwise secured by the purchaser of the article, to the garment as indicated by the numeral 19. The members of a snap fastener 20 are secured to the free ends of the sections 18 and 20 to the ends of the section 17 of the strap and provide means whereby the strap may be temporarily disconnected from the garment substantially in the same manner and for the same purpose as before pointed out.

25 30 From the foregoing description of the invention it will be seen that there is provided a card or tag holder which will effectually protect the card or tag disposed therein and which will prevent loss or displacement of the card or tag and yet permit of its ready removal and replacement.

Having thus described the invention, what is claimed as new is:

1. A device of the class described, comprising a pocket having a mouth, the walls of the pocket adjacent the mouth having openings therein, an attaching strap for attaching the pocket to a garment, the strap being insertable through the said openings to retain within the pocket a card or the like inserted therein, and means for separably connecting the extending portion of the strap to the garment.

2. A device of the class described comprising a pocket having a mouth, the walls of the pocket being provided adjacent the mouth with openings, the rear wall of the pocket being also provided with spaced openings, and a strap attachable to a garment and inserted through the last-mentioned openings whereby to support the pocket, an end portion of the strap being insertable also

through the first-mentioned openings whereby to retain in the pocket a card or the like inserted therein.

3. A device of the class described comprising a pocket having a mouth, the walls of the pocket being provided adjacent the mouth with openings, the rear wall of the pocket being also provided with spaced openings, a strap attachable to a garment and inserted through the last-mentioned openings whereby to support the pocket, an end portion of the strap being insertable also through the first-mentioned openings whereby to retain in the pocket a card or the like inserted therein, and means for separably connecting the last-mentioned end of the strap with the garment.

4. A device of the class described comprising a pocket having front and back walls, the back wall being provided with slots in its intermediate portion and with other slots near its opposite margins, both the front and back walls of the pocket being provided with slots adjacent the said opposite margins, said walls of the pocket at said margins being mutually unattached whereby the pocket is provided with a mouth at either side, and an attaching strap for the pocket threaded through the slots in the back wall of the pocket and having its end portions threaded through the last-mentioned slots in both the back and front walls whereby to constitute means for retaining in place a card or the like inserted in said pocket.

5. A device of the class described comprising a pocket having front and back walls, the back wall being provided with slots in its intermediate portion and with other slots near its opposite margins, both the front and back walls of the pocket being provided with slots adjacent the said opposite margins, said walls of the pocket at said margins being mutually unattached whereby the pocket is provided with a mouth at either side, an attaching strap for the pocket threaded through the slots in the back wall of the pocket and having its end portions threaded through the last-mentioned slots in both the back and front walls whereby to constitute means for retaining in place a card or the like inserted in said pocket, and means for separably connecting either end of said strap with a garment.

In testimony whereof I affix my signature.
JAMES M. BRADY. [L. S.]
